UNITED STATES PATENT OFFICE.

CLARENCE A. FISHER, OF HOUSTON, TEXAS.

CLOTHES DRIER.

Application filed June 6, 1927. Serial No. 196,923.

This invention relates to new and useful improvements in a clothes drier.

One object of the invention is to provide an apparatus of the character described by 5 means of which garments such as dresses and skirts may be quickly dried after having been freshly cleansed and consequently is very useful to clothes cleaners. While the apparatus has been particularly designed 10 for drying dresses and dress skirts it is also applicable for use in drying blouses, shirts, and other garments.

Another object of the invention resides in the provision of an apparatus of the character 15 described having a novel type of fan guard with a motor suspended therein and operatively connected with a fan for generating an air current upwardly through the garment to be dried.

20 A further feature of the invention resides in the provision of adjustable means for holding the lower edge of the garment in position above the fan so that the air current generated by the fan will pass upwardly into the garment and out through the fabric thereof to facilitate the drying of a freshly cleaned garment.

With the above and other objects in view the invention has particular relation to certain 30 novel features of construction, operation and arrangement of parts, an example of which is given in this specification and illustrated in the accompanying drawings, wherein:—

35 Figure 1 is a side elevation of the apparatus, shown partly in section.

Figure 2 shows a sectional view taken on the line 2—2 of Figure 1, and

40 Figure 3 is a horizontal sectional view taken on the line 3—3 of Figure 1.

Referring now more particularly to the drawings wherein like numerals of reference designate similar parts in each of the figures, the numerals 1 and 2 designate upper and lower rings preferably circular in form which are anchored together by the vertical bars 3 spaced apart therearound and arranged in pairs. A supporting framework is thus formed which supports the 45 reticulated cylinder 4 forming a guard, preferably formed of wire mesh and which is secured between the outer and inner bars of each pair of bars 3.

The fan guard has a reticulated cover 5 preferably formed of wire mesh whose margin is secured to the ring 6 which may be

fitted over the upper ring 1 of the framework. There is a cross bar 7 in the fan guard whose ends are anchored to the opposing inside bars 3 and connected to and depending from this cross bar 7 there is a suitable electric motor 8 having the vertical shaft 9 which extends above the motor and to which the fan 10 is secured, formed of the usual inclined vanes, the inclination of the vanes being such that an upwardly directed air current is generated by the fan. Fixed to the framework of the guard there is an upstanding supporting rod 11 adjustable on which is a transversely disposed arm 12 whose free end is adapted to receive a suitable garment hanger to hold the garment suspended over the fan guard. The electric motor 8 is controlled through a suitable switch 13 carried by the rod 11. The guard cover 5 has the cross bars 13' formed with the dovetailed mortises 14 and at each end of each cross bar 13' there is an upstanding anchor 15 whose lower ends have tenons 16 which work in said mortises. Each tenon 80 has an upstanding outwardly threaded stud 17 fixed thereto on which the clamp nuts 18 are threaded. Secured to the upper end of each anchor 15 there is the spring clamp 19 adapted to grip and hold the lower margin 85 of the garment to be dried.

In application the garment to be dried is suspended from the free end of the arm 12 by the conventional garment hanger. The lower margin of the garment is inserted into 90 the clamps 19 and the fan 10 is rotated so as to blow the air upwardly through the garment at high speed and the air will be forced outwardly through the fabric of the garment. The spring clamps 19 are radially 95 adjustable, as the garments to be dried are of various widths and said clamps may be adjusted so as to accommodate the particular garment being dried.

While I have shown and described one 100 form of the invention which I now consider to be the preferred form it is apparent the mechanical changes may be made in the structure and equivalents substituted for the parts shown and I hereby reserve the 105 right to make such changes as may be found practical or desirable so long as I do not depart from the scope of the appended claims.

What I claim is:

1. In an apparatus of the character described, the combination of a reticulated

guard, a reticulated cover for said guard, a cross bar in the guard, a motor connected to and depending from said cross bar and having an upwardly extended shaft, a fan on said shaft, a supporting rod attached to the guard and extending above said guard, a cross arm carried by said rod and extending over said cover and adapted to support a garment hanger and radially adjustable means on said cover for gripping the lower margin of the garment suspended from said hanger.

2. In an apparatus of the character described the combination of a framework and a reticulated guard supported thereby, a transverse cross bar in said guard, a motor connected to and depending from said cross bar and having an upwardly extended shaft, an upward delivering fan fixed to said shaft, an upstanding supporting rod associated with said guard, a cross arm carried by said rod and extending over said guard and adapted to support a garment hanger, cross bars at the upper end of the framework, radially adjustable gripping means carried by said cross bars and formed with clamps adapted to grip and hold the lower margin of a garment suspended from said hanger.

3. In an apparatus of the character described, the combination of a framework

formed of upper and lower rings, vertical bars connecting said rings, a reticulated cylinder supported by said framework forming a guard, a reticulated cover for said guard, a cross bar located within said guard, a motor anchored to the cross bar and depending therefrom and having an upwardly extended shaft, a fan fixed to said shaft, an upstanding rod associated with said guard, a cross arm carried by the rod and extending over said cover and adapted to support a garment hanger, cross bars above said cover and spring clamps on said cross bars for engaging and holding the lower margin of the garment suspended from said hanger, said clamps being radially adjustable.

4. An apparatus of the character described the combination of a reticulated guard and a reticulated cover for said guard, an upwardly delivering fan in said guard, a supporting rod associated with the guard and extending above it, a cross arm carried by said rod and extending over said cover and adapted to support a garment hanger and a plurality of radially adjustable gripping means carried by said cover for gripping and holding the lower margin of the garment suspended from said hanger.

In testimony whereof I have signed my name to this specification.

CLARENCE A. FISHER.
